(57) **CLAIM**

The ornamental design for a LED light string insulation core, as shown and described.

DESCRIPTION

FIG. 1 is a perspective view of a LED light string insulation core showing my new design;

FIG. 2 is a front elevational view thereof, the rear elevational view is identical;

FIG. 3 is a left elevational view thereof, the right elevational view is identical; and,

FIG. 4 is a top side view thereof, the bottom plan view is identical.

1 Claim, 3 Drawing Sheets(56)
